UNITED STATES PATENT OFFICE.

JOHN F. HOLSCLOW, OF ALBIA, IOWA.

SWITCH-OPERATOR.

1,275,428.

Specification of Letters Patent. Patented Aug. 13, 1918.

Application filed November 7, 1917. Serial No. 200,817.

To all whom it may concern:

Be it known that I, JOHN F. HOLSCLOW, a citizen of the United States, residing at Albia, in the county of Monroe and State of Iowa, have invented certain new and useful Improvements in Switch-Operators, of which the following is a specification.

This invention relates to switch operating devices, more particularly to the switches of trolley or street car lines, and has for one of its objects to provide a device of this character which may be operated by the motorman or other person upon the car and without stopping the car.

Another object of the invention is to provide a device of this character which may be arranged externally of the rails or between the rails without material structural change either in the mechanism upon the car or the switch actuating mechanism.

With these and other objects in view, the invention consists in certain novel features of construction, as hereinafter shown and described and then specifically pointed out in the claims; and in the drawings illustrative of the preferred embodiment of the invention—

Figure 1 is a plan view of a conventional trolley or street car line switch with the improvement applied externally of the rails.

Fig. 2 is a diagrammatic view of a portion of a trolley or street car, illustrating the construction of the car carried portion of the apparatus.

Fig. 3 is an end view of the parts shown in Fig. 2.

Fig. 4 is a sectional detail illustrating the construction of the shipper lever.

Fig. 5 is an enlarged transverse section on the line 5—5 of Fig. 1.

Fig. 6 is a view similar to Fig. 1 showing the switch operating mechanism arranged midway between the rails.

Fig. 7 is an enlarged transverse section on the line 7—7 of Fig. 6.

Fig. 8 is a view similar to a portion of Fig. 6 showing the switch operating mechanism arranged just inside the switch rail.

The improved device is designed more particularly for operating the switches of trolley and street car lines, and for illustration is shown thus applied, but it will be obvious that the improved device may be adapted for steam railroads by making a

few minor and unimportant changes in the 55 details of the construction.

In the ordinary trolley or street car lines the switch rail or "point", represented conventionally at 10, is in the form of a relatively long bar tapered toward one end and pivoted at 11 in a seat in a relatively heavy base member 12, with one of the main line rails 13 abutting against the member 12. At its free end the switch rail 10 is adapted to be seated in a socket 15 when in closed position as shown in Fig. 1, and into a similar socket 14 when in open position as shown in Figs. 6 and 8. The "frog" is represented at 16, of the usual construction with the other main line rail 17 abutting against the frog 70 device. One of the siding rails 18 abuts against the ends of the base member 12 of the switch, while the other siding rail 19 abuts against the frog 16 as shown in Figs. 1 and 6. The switch bars 10 are usually 75 manually operated either by a switchman or the motorman or conductor of the approaching car, and when manipulated by the conductor or motorman the car must be stopped before it passes the switch, and again after the car passes the switch to enable the conductor or motorman to reset the switch bar before passing onward. The device which is the subject matter of the present application is designed to enable the 85 motorman or other attendant to actuate the switch from the car and without stopping the car, and dispensing with a switch attendant.

The improved device includes an actuating bar 20 pivoted at one end as shown 90 at 21, and preferably diverging toward the free end as shown in Figs. 1, 6 and 8. When the operating bar 20 is located externally of the rails, a base member 22 is provided which may be integral with the member 12, 95 and is formed with a guide rib or guard rail 23 at one edge, the guard rail being spaced from the pivot end of the bar. When thus arranged the portions of the main and siding rails adjacent to the base member 12 forms 100 another stop or guide at the opposite side of the bar 20 from the stop rail 23, and also spaced from the pivoted end of the bar, as shown in Fig. 1. Near its free end the bar 20 is coupled to the switch rail 10 by a rod 105 device 24, the latter being pivotally united respectively at 25—26 to the members 10 and 20. The rod 24 extends downwardly

and beneath the base members 12 or 22, as the case may be, and as illustrated in Figs. 5 and 7. The base member 12 is provided with a transverse slot 27 where the coupling member 24 is located, while the extension 22 is likewise provided with a similar slot 28, to permit free play to the bars 10 and 20. When the switch operating device is located between the rails, as shown in Figs. 6, 7 and 8, the supporting member 22 will be coupled directly to the supporting ties and located at any point between the rails, and the coupling member 24 increased in length, but otherwise the mechanism is substantially the same whether the operating device be located externally of the rails or between the rails.

When the bar 20 is located between the rails, a second stop rail 23' will be employed as shown in Figs. 6 and 8. Converging recesses are thus formed at opposite sides of the bar 20, the object to be hereafter explained.

By this arrangement it will be obvious that if the member 20 be caused to move laterally upon its pivot 21 the free end of the switch bar 10 will be moved a corresponding distance. Thus when the member 20 is in one position as shown in Fig. 1, the switch bar 10 will be maintained in closed position to guide the car upon the main line, and if the member 20 be reversed in position, the switch bar 10 will be moved into open position as shown in Fig. 6.

The mechanism for actuating the member 20 is mounted upon the approaching car, and comprises a radius bar 29 pivoted at one end at 30 to the framework of the car, the latter indicated conventionally at 31. Pivoted at 32 to the framework of the car is an operating lever 33 passing up through the deck of the car in convenient position for the motorman. At its lower end the lever 33 is provided with a lateral offset or arm 34 coupled by a pivoted link 35 to the member 29. The member 29 supports a disk 36 at its free end preferably with its edge relatively sharp or V-shaped as shown in Fig. 3. By this arrangement it will be obvious that when the lever member 33 is moved longitudinally of the car in one direction, the rod or support 29 and the disk 36 carried thereby will be elevated, or maintained in inoperative position and when moved in the opposite direction, the disk will be depressed.

The member 29 is arranged to be moved laterally as well as vertically to so adjust the disk 36 as to cause it to pass to either side of the pivoted end of the bar 20, and an approved means of accomplishing this result is illustrated in Fig. 4, consisting in so forming the bracket 38 whereby the lever 33 is cou-

pled to the car, as to permit the lever to swing laterally independently of its swinging movement on the pivot 32.

65

By this arrangement, it will be obvious that if the lever 33 be moved laterally in one direction at the same time that it is moved longitudinally of the car to depress the disk, the latter will be caused to enter the space indicated at 37 between the member 20 and the guard rib 23, and then as the car moves forward the disk will engage the member 20 and throw the latter over to one side and thus operate the switch bar 10 and move it into the position shown in Fig. 3, and thus cause the car to run upon the siding.

70

Then if the lever 33 be moved in the opposite direction at the same time that it is moved to depress the disk, the latter will also be moved laterally and caused to enter the space indicated at 39, between the bar 20 and the adjacent edge of the base 12 or the rib 23' as the case may be, and throw the bar over in the opposite direction and close the switch to conduct the car upon the main line.

80

Thus if the switch is "set" for the siding and an approaching car is to go on the main line, the motorman can throw the switch to the required position by properly manipulating the lever 33.

85

The improved device is simple in construction and can be attached to cars of various sizes and construction without material structural change, and may be located upon any portion of the car to adapt the device to the location of the switch actuating mechanism.

95

Having thus described the invention, what is claimed as new is:

1. In a switch operating device, a base member, guide ribs rising from the base in spaced relation and approaching each other intermediate the ends, and a switch bar 105 adapted to be coupled to a switch point and pivoted at one end between the terminals of the ribs with its free end pointed and terminating near the nearest approach of the ribs, whereby converging approaches are provided at both ends of the bar.

110

2. The combination with a railway switch including a movable point member, of a base member, guide ribs rising from the base in spaced relation and approaching each other intermediate the ends, and a switch bar adapted to be coupled to a switch point and pivoted at one end between the terminals of the ribs with its free end pointed and terminating near the nearest approach of the ribs, whereby converging approaches are provided at both ends of the bar.

115

In testimony whereof I affix my signature.
JOHN F. HOLSCLOW. [L.S.]
